UNITED STATES PATENT OFFICE.

ERNEST JAMES WESTCOTT HOUSDEN, OF CROYDON, ENGLAND.

APPARATUS RELATING TO GAMES AND PASTIMES.

Application filed October 22, 1928, Serial No. 314,133, and in Great Britain July 12, 1927.

This invention relates to apparatus relating to games and pastimes and has for its object the provision of apparatus which will both facilitate practice of the game of golf 5 and in a measure provide for a substantially new game played with golf clubs and golf balls.

The invention consists broadly of a golf practice appliance comprising a target having a surface of such a degree of plasticity that a golf ball, when driven against it, makes a depression at any portion of its area where such ball strikes which depression may afterwards be smoothed out.

15 The plasticity is preferably such that the ball on striking the target will make a depression and just rebound in a substantially spent condition.

20 In order that the invention may be the more clearly understood a target structure in accordance therewith will now be described reference being made to the accompanying drawings, wherein:—

25 Figure 1 is a perspective view of the whole structure erected for use.

Figure 2 is a plan of the target proper.

Figure 2^A is a rear elevation of the target proper.

30 Figure 3 is a sectional side elevation to an enlarged scale of part of said structure.

Figure 4 is a front perspective view to an enlarged scale of part of the target proper.

35 Thus the target proper consists essentially of a sheet of plastic material 1 located in the cavity of a frame. The plasticity of said material is of such a degree that a golf ball when driven at it from a distance of say ten or twelve feet forms a clearly visible depression such as *a* and then just rebounds in a substantially spent condition.

40 This target proper is erected in an upright position and a piece of hemp twine net 2 extends forwardly from the upper, and two side edges of the material 1, as indicated somewhat diagrammatically in

45 Figure 1, so as to constitute a safety enclosure.

Said frame comprises a rectangular back board 3 (which may be in two parts as shown in Figure 2) and four frame members 4 secured on the front surface thereof flush with the edges so as to define the cavity in which the material 1 is contained.

50 Said back board may be reinforced by means of three upright members 5 (the outer two of which may be of double thickness as shown) and four cross members 6 secured at the back of

said back board respectively by bolts 7 and nails 8 as shown. Alternatively said back board may be made of double ply boarding and not reinforced. To assist in anchoring the material 1 in place a piece of wire netting 9 preferably doubled is secured by means of a number of staples (not shown) against the front surface of the back board 3.

55 The net 2 is secured to the edges of the target proper as clearly shown in Figure 3 by means of strips of beading 10 and it should be noted that the members 4 are bevelled so that the front and outer surfaces nearly join as at *b*. As the drawing clearly shows, this 60 ensures that the outer limits of the front surface of the material 1 are in very close proximity to the netting 2 so that there is no hard edge from which a badly struck ball might 65 rebound.

70 The surface of the target is marked out into areas of different value by means of lengths of elastic 11 arranged in concentric rectangles as shown. These lengths of elastic are located by being passed at the four corners of 75 each rectangle completely through holes 12 in the target to the back of the back board 3 where they are secured to short cross pegs of wood 13 as shown.

75 The material 1 is a composition consisting of petroleum jelly and a stiffening medium such as calcium carbonate and china clay. Paraffin wax, barytes, oil and a suitable colouring medium are also preferably added. The following percentages by weight have 80 been found satisfactory:—

	Per cent.
Petroleum jelly	14
Oil	14
Calcium carbonate	25
China clay	25
Barytes	14
Colour medium	2
Paraffin wax	6

85 In manufacture, the frame having been constructed the petroleum jelly and paraffin wax are boiled together and the calcium carbonate, china clay, barytes and oil are added in small quantities to the boiling mass the colouring medium being added last. The frame is then laid horizontally with its face 90 up and the boiling composition is poured into the cavity thereof and permitted to cool. The elastic 11 is then located and the netting secured as described.

100 When a given number of balls have been driven at the target the indentations may be 105

110

easily smoothed out either by the hand or by means of a suitable roller. Should a ball strike one of the lengths of elastic it will make a depression behind said elastic; and the latter, by virtue of its resiliency, may be lifted from the surface of the material 1 to enable said depression to be obliterated.

The netting 2 is supported by means of vertical and horizontal metal frame members 10 constructed and arranged as clearly shown in Figure 1 of the drawings.

What I claim and desire to secure by Letters Patent is:—

1. A golf practice appliance comprising a target surface of such a degree of plasticity that a golf ball, when driven against it, makes a depression at any portion of its area where such ball strikes which depression may afterwards be smoothed out and lengths of elastic marking said surface into areas.

2. A golf practice appliance comprising a target frame affording a suitable cavity, plastic material located within said cavity and forming a target surface said material being of such a degree of plasticity that a golf ball, when driven against it, makes a depression at any portion of its area where such ball strikes which depression may afterwards be smoothed out and lengths of elastic marking said surface into areas.

3. A golf practice appliance comprising a target frame affording a suitable cavity, plastic material located within said cavity and

forming a target surface said material being of such a degree of plasticity that a golf ball, 35 when driven against it, makes a depression at any portion of its area where such ball strikes which depression may afterwards be smoothed out and lengths of elastic marking 40 said surface into areas and netting secured to said frame and extending forwardly from the close proximity of the outer limits of said surface.

4. A golf practice appliance comprising a target frame affording a suitable cavity, plastic material located within said cavity and forming a target surface said material being of such a degree of plasticity that a golf ball, 45 when driven against it, makes a depression at any portion of its area where such ball strikes which depression may afterwards be smoothed out and lengths of elastic marking 50 said surface into areas and means tending to anchor said material within said frame.

5. A golf practice appliance, consisting of 55 a target comprising a single section having a surface of such a degree of plasticity that a golf ball, when driven against it, makes a depression at any portion of its area where such ball strikes and just rebounds in a substantially spent condition leaving said depression which may afterwards be smoothed out, said surface comprising petroleum jelly, a stiffening medium and paraffin wax.

In witness whereof I affix my signature.
ERNEST JAMES WESTCOTT HOUSDEN.
